UNITED STATES PATENT OFFICE.

OTIS A. MYGATT, OF NEW YORK, N. Y.

DESIGN FOR A SHADE OR SIMILAR ARTICLE FOR ARTIFICIAL LIGHTS.

40,607.

Specification for Design.

Patented Apr. 5, 1910.

Application filed June 5, 1908. Serial No. 436,999. Term of patent 14 years.

To all whom it may concern:

Be it known that I, OTIS A. MYGATT, a citizen of the United States, residing in the city and State of New York, have invented a new, original, and ornamental Design for Shades or Similar Articles for Artificial Lights, of which the following is a specification, reference being had to the accompanying drawing, forming a part thereof.

The drawing is a bottom perspective showing the design of the article.

I claim:

The ornamental design for a shade, or similar article, for artificial lights, as shown.

OTIS A. MYGATT.
